United States Patent Office.

JOHN A. BATCHELOR, OF NEW YORK, N. Y.

Design No. 4,942, dated May 30, 1871.

DESIGN FOR CLOCK-FRONT.

The Schedule referred to in these Letters Patent and making part of the same.

I, JOHN A. BATCHELOR, of the city, county, and State of New York, have invented and produced a new and original Design for Clock-Fronts, of which the following is a specification.

The nature of my design is fully represented and embodied in the accompanying photographic illustrations, to which reference is made, and which form a part of this specification.

I claim as my invention—
The design for a clock-front embodied and shown in the accompanying photographs.

JOHN A. BATCHELOR.
